CLAIM

We claim the ornamental design for a multimedia box, as shown and described.

DESCRIPTION

FIG. 1 is a first perspective view of a multimedia box incorporating our new design;

FIG. 2 is a second perspective view thereof;

FIG. 3 is a top view thereof;

FIG. 4 is a front view thereof;

FIG. 5 is a left side elevational view thereof, the right side elevational view being a mirror image thereof;

FIG. 6 is a bottom plan view thereof; and,

FIG. 7 is a rear view thereof.

The broken lines environmental are for illustrative purpose only and form no part of the claimed design.
